UNITED STATES PATENT OFFICE.

HENRY W. HIRSCHFELD, OF MERIDEN, CONNECTICUT, ASSIGNOR TO THE MERIDEN BRITANNIA COMPANY, OF SAME PLACE.

DESIGN FOR SPOON AND FORK HANDLE.

SPECIFICATION forming part of Design No. 12,137, dated January 18, 1881.

Application filed October 20, 1880. Term of patent 7 years.

To all whom it may concern:

Be it known that I, HENRY W. HIRSCHFELD, of Meriden, in the county of New Haven and State of Connecticut, have invented a new 5 Design for Spoon and Fork Handle; and I do hereby declare the following, when taken in connection with the accompanying drawing and the letters of reference marked thereon, to be a full, clear, and exact description of the 10 same, and which said drawing constitutes part of this specification, and represents a front view.

This invention relates to a design for the 15 handle of spoons, forks, and like articles of table service; and it consists in the ornamentation of the handle, as shown in the accompanying illustration.

In outline the handle gradually expands from 20 its narrowest part to the end, where it terminates in segment shape. On the surface at the end is a segment-shaped border, *a*, composed of a bead above and below, filled with a series of small rose-shaped figures, and below the border *a* is a transverse band, *b*, consisting of a bead above and below, with a "herring-bone" filling, and the space between the

segment-shaped border and the band *b* below is filled with a tracery of scroll-work. At the end outside the band there is a rose-tip, *c*, projecting one-half its diameter above, and at 30 each side the end of the handle is escalloped. From the narrower portion to about two-thirds the length of the handle the surface is checked, terminating in a semi-quarterfoil bead. At the upper end on this checked surface is a 35 floriated vine with a bird hovering thereon, all as shown in the accompanying illustration.

I claim—

The design for spoon-handle, consisting of the ornamental segment-shaped border *a* and 40 transverse band *b* at the tip, with a checked surface extending from the narrower portion toward the end, and terminating on the surface in a semi-quarterfoil bead, with floriated tracery, and the representation of a bird on 45 said checked surface, all as shown in the accompanying illustration.

H. W. HIRSCHFELD.
